Patented Dec. 3, 1918.

UNITED STATES PATENT OFFICE.

GEORGE T. JOHNSON, OF MELROSE, MASSACHUSETTS, ASSIGNOR TO THE GEORGE T. JOHNSON COMPANY, OF BOSTON, MASSACHUSETTS, A CORPORATION OF MASSACHUSETTS.

DISPENSING APPARATUS FOR ROLL MATERIAL.

1,286,599.

Specification of Letters Patent. Patented Dec. 3, 1918.

Application filed February 25, 1915. Serial No. 10,577.

To all whom it may concern:

Be it known that I, GEORGE T. JOHNSON, a citizen of the United States, residing at Melrose, in the county of Middlesex, State 5 of Massachusetts, have invented a certain new and useful Improvement in Dispensing Apparatus for Roll Material, of which the following is a specification, reference being had therein to the accompanying drawings.

10 The invention relates to apparatus of the general class designed to enable short lengths to be taken from the outer end of a continuous strip or web that has been wound into a roll. More especially, it has 15 relation to apparatus of those kinds which are constructed to check the revolution of the supply-roll after it has revolved a pre-determined distance in unwinding, so as, by the checking, to render a pull by the 20 user upon the unwound portion of the so-called web effective in causing the parting of the strip or web, usually at a transverse line of weakness, whereby to detach a portion which has been unwound from the roll. 25 Such apparatus has been proposed for use in dispensing or serving toilet paper and paper toweling.

In the case of prior constructions employed in practice, so far as known to me, 30 the roll at every unwinding operation always revolves to the same angular extent before being checked. From this it results that the lengths of material that are paid off from the roll at successive unwinding 35 operations vary according to the varying diameter of the wound supply at the times of such operations. With a full roll, the latter being of its largest diameter and consequently having its largest peripheral 40 measurement, the length of material paid off by the roll in revolving to a given angular extent in unwinding will be very much greater than the length which will be paid off when the wound mass has become sub- 45 stantially exhausted so that its diameter and consequently its peripheral measurement are much smaller. This lack of uniformity in the lengths successively paid out in the case of an apparatus of one of the prior construc- 50 tions is objectionable, because when a roll is of the usual commercial size and has lines of weakness spaced at the usual distance apart, the length of material which is paid off therefrom at first by an unwinding oper- 55 ation is excessive, and may include two or

more successive lines of weakness, resulting in the detaching of more than the intended length of strip material, whereas before the roll has become exhausted the length paid off by an unwinding operation is shorter 60 than is desired and the next line of weakness does not leave the wound mass. When the line of weakness has not left the wound body of the roll, the detachment of the drawn-off portion is difficult and usually 65 can be effected only by tearing the material across its width at some place short of the said line of weakness.

A general object of the invention is to so improve the mode of operation of dispensing 70 or serving apparatus for roll material as to obviate the paying-out of a needlessly great length of material at an unwinding operation while the roll is full or approximately full, and the paying-out of a deficient length 75 as the roll approaches exhaustion. I aim to avoid, when material having transverse lines of weakness at regular intervals apart is employed, the paying-out of the web past two or more successive lines of weakness in 80 the case of a full roll and the stopping short of paying-out to the first line of weakness as the roll approaches exhaustion. In other words, the object is to render the paying-out at successive deliveries substantially 85 uniform in amount, unaffected by variations in the size of the wound supply.

The invention provides an improved dispensing or serving apparatus in which the unwinding revolution of the roll produces 90 a traveling movement of the latter bodily, in a direction that is transverse with relation to the roll-axis, until such traveling bodily movement is arrested, thereby arresting the unwinding revolution so that pulling 95 upon the portion of material that has become unwound causes the material to part at a line of weakening which has passed off from the wound roll. A characteristic feature of the invention is a starting-position 100 gage operating to determine the starting position of the roll through the contact of the periphery of the wound supply therewith. The unwinding revolution of the roll causes the latter to travel away from the 105 said starting-position gage. The return movement of the roll following the delivery causes the periphery of the wound supply to bring up against such gage again. As the wound supply decreases in diameter, the 110

return movement of the roll increases in extent, thereby varying the starting position of the roll-axis, so that the bodily travel or traverse of the roll in unwinding is increased in extent by a gain at the starting end of the said travel or traverse. The increased extent of travel or traverse permits an increased extent of unwinding revolution of the roll before the travel or traverse during the unwinding operation is arrested.

The invention includes also a construction of the said apparatus by which twisting and cramping of the parts in operation, and interference with the free and easy action thereof, are obviated.

Other objects of the invention are to provide in improved manner for the connection of a roll of wound material with the roll-support of a dispensing fixture or apparatus of the general class aforesaid so as to cause them to revolve in unison, and to provide an improved means for locking the roll-support and roll in working relation. For attaining the first of these objects, the invention comprises a dispensing fixture or apparatus having a roll-support and constructed to permit unwinding revolution of said roll-support, said roll-support adapted for engagement with the roll by an endwise screwing-on movement to a stop-limit by relative turning in the direction of the unwinding revolution produced by a pull upon the free end of the wound material. For attaining the second of the said objects, the invention includes an improved lock.

An illustrative embodiment of the invention is shown in the drawings in which later,

Figure 1 is a side elevation of a dispensing or serving apparatus containing the said embodiment.

Fig. 2 is a view mainly in section on line 2, 2, of Fig. 1.

Fig. 3 is a detail view in section on line 3, 3, of Fig. 2.

Fig. 4 is a partly-sectional view in section showing the screw-threaded end-portion of the roll-support and the corresponding end-portion of the roll-core.

Fig. 5 is a similar view of the same parts as Fig. 4, but representing them as separated from each other.

Fig. 6 is an isometric view of the screw-threaded internal ferrule I apply to the roll-core.

Fig. 7 is an isometric view of the end of the roll-core which is located at the swing-end of the roll-support.

Having reference to the drawings,—

The apparatus or fixture shown therein has a supporting-frame or bracket comprising a longitudinal backing-bar or plate 1 and side-arms 2, 2. The wound roll 3 containing the supply of material is mounted between the said side-arms in a manner pro-

viding for the required bodily traveling movement of the roll. In this instance slots 4, 4, in the said side-arms receive axial extensions from the opposite ends of the roll. The slots permit the said traveling movement, and guide the roll as it travels. The means for producing the traveling movement in consequence of the revolution of the roll in delivering the wound strip when the free end 3^a of the strip is pulled upon may vary in practice. Preferably for the said purpose, I provide teeth in connection with the said axial extensions, constituting spur-pinions 5, 5, and furnish one wall of the slot 4 in each side-arm with teeth forming a rack 6. The two pinions 5, 5, are in engagement with the two racks 6, 6. The pinions are connected with the roll in such a manner that when the roll is caused to revolve by pulling upon the free end 3^a of the strip the pinions revolve in unison with the roll, and as a result of the engagement of the pinions with the racks the revolution of the pinions causes them and the roll to travel along the racks. The traveling movement is arrested by stops 7, 7, with which the side-arms 2, 2, are furnished, arranged to act as presently will be explained, and the arrest of such movement operates to arrest the delivery of the material from the roll because when the pinions are prevented from traveling along the racks the interengagement of the teeth of the racks and pinions prevents revolution of the pinions and roll. The continued pull upon the outer end 3^a of the said material after further revolution has been prevented, aided by the shock incident to the sudden arrest of revolution and delivery, operates to tear the material across at a line of weakening that has passed off from the body of the wound mass. The roll then travels reversely to starting position, where it remains in readiness for a second dispensing operation.

The starting-position gage is constituted in this instance by a cross-bar 8, that is attached by its opposite ends to the side-arms 2, 2, and thereby supported in working position in proper relation with the starting-ends of the racks 6, 6. The peripheral surface of the wound material rests against the said gage when the roll occupies its starting position. The radial thickness of the wound material determines the starting position of the roll, and thereby determines the points in the length of the racks at which the pinions 5, 5, will rest while the roll is in the starting position. In proportion as the wound roll diminishes in diameter, the axis of the roll will approach nearer to the starting-position gage, and the pinions will assume positions nearer the said starting-ends of the racks and at the same time farther from the stops 7, 7. Consequently the distance traveled by the roll-axis before the

traveling movement of the roll is arrested by the stops, and the angular extent of the revolution of the pinions and roll in unwinding, will increase in proportion as the diameter of the wound roll decreases. In this manner, as a result of the employment of the starting-position gage, and of permitting the pinions to approach more closely toward the starting ends of the racks in proportion as the wound supply diminishes in diameter, the diminution in diameter is compensated for so that at all times until the wound supply has been completely unwound a sufficient length is permitted to unwind from the roll at each dispensing operation to present a line of weakening so as to facilitate the detaching of the proper length for a single service. In other words, the successive deliveries at successive dispensing operations are rendered substantially uniform in length and thereby the presentation of a line of weakening in proper position to facilitate the detaching of the predetermined length for a single service, at every operation, is insured.

The roll may be caused variously to return to starting position and coact with the starting-position gage. Springs may be employed for the purpose, and the arrangement of the parts may vary. In the illustrative embodiment of the invention that is herein shown gravity is utilized, the said gage being placed below the roll, the slots being upright, or substantially so, so that when the roll is free to do so it gravitates downward until its periphery rests against the gage. The racks and pinions are so arranged that when the free end ^{3a} of the strip is pulled upon, the roll travels upward as it delivers the material, until its upward movement is arrested by the stops ^{7, 7}. As soon as the material is broken or torn across so as to relieve the pull upon the portion remaining upon the roll, the roll sinks by gravity to the starting position.

The starting-position gage ⁸ may be constructed, as shown, to make contact with the periphery of the wound roll ³ at and near the ends of the latter only, and not make contact with the intermediate portion of the length of the roll. The said gage is shown bent away from the said intermediate portion of the roll so as to afford access to such portion. If the free end of the strip should happen to be located between the roll and the gage, instead of hanging down clear of the latter as in Figs. 1 and 2, the clearance that is afforded by the said construction of the gage gives convenient access to the said free end, so that it may be grasped to draw the material from the roll.

The pinions ^{5, 5}, are fixed upon journals ^{9, 10}, at the opposite ends of the roll-supporting means. Equal movement of the said pinions in traveling along the racks is

insured, and thereby twisting and cramping of the parts in operation and interference with the free and easy action thereof are obviated, by the employment of opposite swinging arms ^{11, 11}, respectively engaging with the respective journals and themselves joined together so that they swing in unison about a transverse axis that is located adjacent the backing-bar ¹. The swinging arms ^{11, 11}, are joined together by being fixedly mounted upon the opposite ends of a cross-shaft ¹². The swinging movements of the said arms are provided for by mounting the said shaft ¹² in bearings in the opposite fixed arms ^{2, 2}, with capacity to rock in the said bearings. The free extremities of the arms ^{11, 11}, are slotted to receive the journals ^{9, 10}. The slots ^{4, 4}, in the fixed side-arms ^{2, 2}, are concentric with the axis of the cross-shaft ¹² and so are also the racks ^{6, 6}, and hence the roll and its pinions travel in curved paths. By means of the cross-shaft ¹², and its arms ^{11, 11}, the pinions ^{5, 5}, are kept exactly opposite each other, and in engagement with corresponding portions of the respective racks. Thereby cramping and twisting are obviated and ease of movement is insured.

The journals ^{9, 10}, and pinions ^{5, 5}, are in this instance connected with a roll-support upon which the roll ³ is mounted. The said roll-support comprises, mainly, opposite flanged heads ^{13 and 14}, and a shaft or body-portion ¹⁵. Head ¹³ is connected with the journal ⁹ by a hinge-connection which permits the said head and the shaft or body-portion to be swung relative to the said journal to facilitate the application of the wound roll to the roll-support, and the removal of the roll-core ^{3b} from the roll-support when the supply of material wound upon the said core has become exhausted. The said hinge-connection is formed by a pair of lugs ^{13a, 13a}, projecting from the outer end of the head ¹³ and receiving between them the inner end of the journal ⁹, the said end being connected with the said lugs by a pivot-pin ^{13b}. The said head has a barrel-portion ^{13c} which is adapted to enter into the central opening at one end of the core ^{3b}. The barrel-portion ^{13c} has a central opening receiving one reduced end-portion of the shaft or body-portion ¹⁵; the said end-portion being fixed therein by suitable fastening means. The opposite end-portion of the shaft or body-portion ¹⁵ is reduced in diameter and has fitted and fastened upon it a cap ¹⁶, which is furnished with a central end-projection ¹⁸ forming a part of the locking means. The flanged head ¹⁴ is mounted upon the journal ¹⁰ with capacity to move lengthwise of the said journal, and is splined to the latter so as to prevent relative turning movement, as by means of a screw ¹⁷, Fig. 2, having its reduced inner ¹³⁰

end entered into a groove 18 formed longitudinally in the journal 10. This construction compels the head 14 and the journal 10 and corresponding pinion 5 to revolve in unison, but permits the said head to be slipped outward along the journal 10 far enough to withdraw its barrel-portion sufficiently to clear the adjacent end of a roll 3 which has been applied to the hinged portion of the roll-support, as the latter is swung inward from its open position into its closed working position. When the said hinged portion and the roll have been swung inward into the latter position, the head 14 is moved inward along the journal 10 so as to push its barrel-portion 14^a into the central opening of the wound roll. With the head 14 is combined a locking member which engages with the projecting end-projection or pin 18^a of the cap 16 to lock the roll-supporting means in closed condition. This locking member comprises a plate 21 of spring material that extends diametrically of the barrel-portion 14^a of the said head, as shown in Figs. 2 and 3. The said spring crosses the central opening of such barrel-portion into which the end-projection or pin 18^a enters. It has a hole 21^a, Fig. 3, to receive the pin 18^a, and is made fast at one end to the said barrel-portion at one side of the latter, its other end being free. This latter end occupies a slot 14^b in the opposite side of the barrel-portion 14^a. In order that the spring and pin may engage with each other, the pin is formed with a reduced neck leaving a head at the end of the pin, as shown in Fig. 2, while the spring occupies an oblique or inclined position, as shown in such figure, which causes the edge of the hole next the free end of the spring to occupy the groove around the neck, so that so long as the spring occupies its normal oblique or inclined position the said edge, by its engagement with the head of the pin, will prevent the flanged head 14 from being moved outward far enough to free the end of the shaft 15. If, however, the free end of the spring be pressed outward so as to cause the spring to assume a position at or approximately at right angles to the axis of the pin, the edge of the hole in the spring will clear the head of the pin, so that the flanged head 14 may be drawn completely outward. When the wound roll 3 contains an ordinary pasteboard tubular core, as 3^b, one end of the latter will cover the slot 14^b and conceal the free end of the spring-catch 21. However, after the wound supply has become unwound the core may be torn away sufficiently to give access to the spring, which will permit the unlocking to be effected. Or the roll-core may be made with a plurality of slots or notches 3^c, 3^d, at its end, as in Fig. 7, one of which notches 65 usually will afford access to the spring.

Endwise screwing-on of the wound roll upon the roll-support to a stop-limit, by relative turning in the direction of the unwinding revolution produced by a pull upon the free end of the wound material, is provided for by forming the roll-support so as to screw partway into the roll. To this end, the hinged flanged head 13 of the roll-support is formed with a coarse screw-thread at 13^a next adjoining its flange, as shown best in Figs. 4 and 5, to screw into the portion of the roll-core 3^b which fits upon the barrel-portion 13^c. A corresponding screw-thread may be provided upon the said portion of the roll-core. If the screw-thread 13^a is sharp, it may bite into the material of the roll-core sufficiently, but preferably I mold a proper thread in the material of the roll-core, or in a short metal tube, 22, which is inserted into the roll-core and fastened in place therein, as by rivets, engaging with ears 22^a, 22^b, provided on the said tube 22, and entering the material of the roll-core. The outer end of the tube 22 is formed into an outturned flange which engages with the corresponding end of the roll-core to limit the extent to which the tube is entered into the roll-core, and facilitate the entrance of the screw-thread 13^a into the end of the tube.

While I have shown the stops 7, 7, herein as constituted by fixed lugs projecting from the inner sides of the side-arms 2, 2, adjustable stops may be employed in practice if deemed desirable.

I claim as my invention:—

1. A dispensing or serving apparatus in which the unwinding revolution of the roll produces a traveling movement of the latter bodily in a direction that is transverse with relation to the roll-axis, and constructed to arrest such traveling movement without contact with the wound material itself to provide for the detachment of the portion of material that has been unwound, and having a starting-position gage which determines the starting position of the roll through the contact of the periphery of the wound supply therewith.

2. A dispensing or serving apparatus constructed to receive a wound roll, and having a gage which determines the starting position of the roll through coöperation with the periphery of the wound supply, means for producing traveling movement of the roll away from the said starting-position gage concurrently with revolution of the roll in delivering the wound material, and means to arrest such traveling movement without contact with the wound material itself when the predetermined amount of material has been unwound.

3. A dispensing or serving apparatus constructed to receive a wound roll, and having a gage which determines the starting position

- of the roll through coöperation with the periphery of the wound supply, means for producing traveling movement of the roll away from the said starting-position gage through the revolution of the roll produced by pulling the end of the material off from the same, and means to define the limit of such traveling movement without contact with the wound material itself.
4. A dispensing or serving apparatus having a roll-support, a gage which controls the starting position of the roll by coöoperating with the periphery of the wound supply, means for producing traveling movement of the roll away from the said starting-position gage through the unwinding revolution of the roll, and means coöoperating with the roll-support to fix the limit of such movement away from the starting-position gage.
5. A dispensing or serving apparatus having a roll-support, a gage which controls the starting position of the roll by coöoperating with the periphery of the wound supply, means coöoperating with the opposite ends, respectively, of the roll-support for producing traveling movement of the roll away from the said starting-position gage through the unwinding revolution of the roll, and means coöoperating with the roll-support to fix the limit of such movement away from the starting-position gage.
6. A dispensing or serving apparatus having a roll-support, a gage which coöperates with the periphery of the wound supply in determining the starting position of the roll, toothed gearing for producing traveling movement of the roll away from the said starting-position gage concurrently with the paying-out revolution of the roll, and stopping means coöoperating with the roll-support to fix the limit of the movement of the roll away from the starting-position gage.
7. A dispensing or serving apparatus having a roll-support, a gage which coöperates with the periphery of the wound supply in determining the starting position of the roll, toothed gearing combined with the opposite ends, respectively, of said roll-support, for producing traveling movement of the roll away from the said starting-position gage concurrently with the paying-out revolution of the roll, and stopping means coöoperating with the roll-support to fix the limit of the movement of the roll away from the starting-position gage.
8. A dispensing or serving apparatus having a roll-support, a pinion operatively combined with said roll-support, a rack with which said pinion gears, a gage which co-
operates with the periphery of the wound supply in determining the starting position of the said pinion relative to the length of the rack, and means defining a fixed limit for the traveling movement of the roll during the paying-out revolution of the roll.
9. A dispensing or serving apparatus having a roll-support, pinions operatively combined with the opposite ends of the said roll-support, racks with which the pinions respectively gear, a gage which coöperates with the periphery of the wound supply in determining the starting position of the said pinions relative to the length of the racks, and means defining a fixed limit for the traveling movement of the roll during the paying-out revolution of the roll.
10. A dispensing or serving apparatus having a roll-support, a gage controlling the starting position of the roll, constructed to make contact with the periphery of the wound roll at and near an end of the latter, leaving the main portion of the length of the roll unobstructed, and means producing concurrent traveling movement and paying-out revolution of the roll.
11. A dispensing or serving apparatus having a roll-support, a gage controlling the starting position of the roll, constructed to make contact with the periphery of the wound roll at and near the opposite ends of the latter, leaving the intermediate portion of the length of the roll clear and accessible, and means for producing concurrent traveling movement and paying-out revolution of the roll.
12. A dispensing or serving apparatus having a roll-support, a pinion operatively combined with said roll-support, a rack with which said pinion gears, means to permit the pinion, in the starting position of the roll, to approach more closely to the starting end of the rack in proportion as the wound supply diminishes in diameter, and means defining a fixed limit for the traveling movement of the roll during the paying-out revolution of the roll.
13. A dispensing or serving apparatus having a roll-support, pinions operatively combined with the opposite ends of the said roll-support, racks with which the pinions respectively gear, means to permit the pinions, in the starting position of the roll, to approach more closely to the starting ends of the racks in proportion as the wound supply diminishes in diameter, and means defining a fixed limit for the traveling movement of the roll during the paying-out revolution of the roll.
14. A dispensing or serving apparatus for material wound in roll-form, having means coöoperating with opposite ends of a roll to produce traveling movement of the roll concurrently with paying-out revolution of the latter, and means coöperating with both of the said ends to compel them to move uniformly and in fixed relation to each other.
15. A dispensing or serving apparatus for material wound in roll-form, having pinions operatively combined with opposite ends of a roll and racks with which said pinions are

- geared to produce traveling movement of the roll concurrently with paying-out revolution of the latter, and means coöperating with both of the said ends to compel them 5 to move uniformly and in fixed relation to each other.
16. A dispensing or serving apparatus for material wound in roll-form, having means at the opposite ends of the roll for producing 10 traveling movement of the roll through the revolution of the roll produced by pulling the end of the material off from the same, and a rocker connecting with both of the said ends and compelling them to move uniformly and in fixed relation to each other.
17. A dispensing or serving apparatus for material wound in roll-form, having pinions oppositely combined with opposite ends of a roll and racks with which said pinions are 20 geared to produce traveling movement of the roll concurrently with paying-out revolution of the latter, and a rocker connecting with both of the said ends and compelling them to move uniformly and in fixed relation to each other.
18. A dispensing or serving apparatus for material wound in roll-form, having means for producing traveling movement of the roll through the revolution of the roll produced by pulling the end of the material off from the same, and opposite arms operatively engaging with opposite ends of the roll and themselves operatively connected together so as to move in unison.
19. A dispensing or serving apparatus for material wound in roll-form, having gearing by which traveling movement of the roll is produced concurrently with paying-out revolution of the latter, and opposite arms operatively engaging with opposite ends of the roll and themselves operatively connected together so as to move in unison.
20. A dispensing or serving apparatus for material wound in roll-form, having a roll-support which is permitted unwinding revolution under a pull upon the free end of the wound material, said roll-support adapted for engagement with the roll by an endwise screwing-on movement to a stop-limit 45 by relative turning in the direction of the unwinding produced by the said pull.
21. A dispensing or serving apparatus for material wound in roll-form, having a roll-support which is permitted unwinding revolution to a limited extent, under the pull 55 upon the free end of the wound material, said roll-support adapted for engagement with the roll by an endwise screwing-on movement to a stop-limit by relative turning in the direction of the unwinding produced by the said pull.
22. A dispensing or serving apparatus for material wound in roll-form, comprising a hinged roll-support adapted to be opened-out for the application of a supply-roll thereto, said roll-support having pinions operatively combined with its opposite ends, and fixed racks with which said pinions engage and along which they are caused to travel by paying-out revolution of the roll.
23. The combination with a roll-support having a screw-thread, and means providing for unwinding revolution thereof under a pull upon the free end of the wound material, of a wound roll having a central 75 threaded portion which screws upon the screw-thread of the roll-support by relative turning in the direction of the unwinding produced by the said pull.
24. In a dispensing or serving apparatus, 80 a roll-support having a body-portion adapted to be moved bodily from its working alinement into position to have a wound roll applied thereto, a longitudinally-movable head adapted to coöperate with said body-portion when the latter is in its working alinement, one of said parts having an axial necked projection, and a locking member carried by the other of the said parts, having an opening to receive the said projection, 85 normally held by spring-tension in an inclined position in which the parts are locked in working relations with the neck in said opening, and adapted to be sprung into a position in which the opening permits the head 90 of said projection to pass therethrough.
- In testimony whereof I affix my signature in presence of two witnesses.
